UNITED STATES PATENT OFFICE.

DIDRICK DYRESEN, OF MALDEN, MASSACHUSETTS.

SEPARABLE FASTENER.

Application filed December 20, 1924. Serial No. 757,155.

This invention aims to provide an improved separable fastener.

In the drawings, which illustrate a preferred embodiment of my invention:

5 Figure 1 is a front elevation of the preferred form of fastener;

Fig. 2 is a section on the line 2—2 of Fig. 1, being partly in elevation;

10 Fig. 3 is a section similar to Fig. 2, but showing the relative positions of the stud and socket during engagement thereof;

Fig. 4 is a rear elevation of the socket;

15 Fig. 5 includes a front, a side and a rear elevation respectively of the stud; and

Fig. 6 is a section on the line 6—6 of Fig. 1.

Referring to the drawings, I have shown a three-side lock fastener which includes a flush type stud and a socket which may be of any one of several well known types of three-

20 side lock fastener sockets.

The stud, as illustrated, includes a casing 1, secured to a support 2, which may be the body of an automobile, by an attaching screw 3 secured to the casing in substantially the

25 same manner as set forth in my co-pending application Serial No. 757,154, filed herewith. The casing presents at its outer end a flange 4 which seats against the outer face of the support 2. Instead of providing the flange

30 4 with a hexagonal periphery as in the above-mentioned co-pending application, I have provided the casing with a hexagonal tool-receiving portion 5 which extends beyond the flange 4 to receive a tool, such as a socket

35 wrench for securing the casing 1 to the support 2. The stud also includes a socket-engaging part having a head 6, a neck 7, a shank portion 8 and base portion 9, as shown in Figs. 2 and 3, the shank portion and the

40 greater portion of the neck of the socket-engaging part being normally surrounded by the casing 1 and held in position by a spring 10 interposed between the base 9 of the socket-engaging part and a depending flange 11

45 located at the outer end of the casing. Thus only the head and a portion of the neck of the socket-engaging part extend beyond the casing 1, prior to engagement with a suitable socket, as illustrated in Fig. 5.

50 While I may use any one of several types of three-side lock fastener sockets, which may be secured to a flexible curtain, I prefer to provide a socket similar to the one referred to in the above-mentioned co-pending

55 application. In this instance, however, the socket casing 12 presents a relatively large

aperture 13 in the face thereof, the purposes of which are more fully hereinafter described. Within the casing, I have provided a plurality of resilient jaws 14 and a fixed jaw 15 which intersect the aperture 13 as shown in Fig. 4.

The socket may be secured to the stud, as shown in Fig. 3, by pressing the casing toward the stud so that the head 6 of the socket-

65 engaging part may pass between the jaws 14 and 15. During this engaging operation, the tool-receiving portion 11 of the stud casing 1 also passes into the aperture 13 in the socket casing 12 and contacts with the jaws 14, so

70 that the fixed jaw 15, which is slightly inclined, may engage the shoulder located between the head and neck of the socket-engaging part. Thus the jaw 15 will wedge or pull

75 the socket-engaging part out of the casing 1 so that the entire neck will be exposed beyond the face of the stud casing 1. The resilient

jaws 14, which have been expanded by the head 6, may then engage the neck 7 of the

socket-engaging part and urge the fixed jaw 80

15 into engagement with the neck of the stud, as illustrated in Fig. 2. The stud and socket will then be locked together against separation by various strains exerted at three sides

85 thereof in substantially the same manner as set forth in the above-mentioned application.

Separation of the socket from the stud is effected by grasping the lower edge of the

90 curtain and exerting a slight outward pull thereon. This action causes the fixed jaw 15 to pull the socket-engaging part outwardly

95 relative to the casing 1, so that the socket may tip relative to the socket-engaging part to permit the head 6 thereof to pass between the jaws 14 and 15. The spring 10 thereafter returns the socket-engaging part to its normal

position.

While I have shown and described a preferred embodiment of my invention, it will be understood that changes involving omission, substitution, alteration and reversal of parts, and even changes in the mode of operation, may be made without departing from the scope of my invention, which is best defined in the appended claims.

100 I claim:

1. A flush type stud comprising a casing having an attaching screw secured in a fixed relation to the inner end thereof, a flange adjacent the outer end thereof to seat against the front face of a support and a tool-receiving portion beyond said flange for receiving

a tool by which said casing may be secured to the support, and shiftable socket-engaging means having a portion thereof protruding through an aperture in the front face of said casing, said socket-engaging means normally urged toward the attaching screw by a spring interposed between a portion of said casing and a portion of said socket-engaging means.

2. A fastener stud presenting, in combination, a casing part, a socket-engaging part axially shiftable relative to said casing part, said socket-engaging part presenting a head and a neck, and spring means interposed between an abutment presented by the casing

and an abutment presented by the socket-engaging part thereby normally pressing said socket-engaging part inwardly relative to the casing, and means cooperating beyond the socket-engaging part and the casing part to limit the inward movement of the socket-engaging part whereby only the head and a portion of the neck of the socket-engaging part are normally exposed beyond the outer end of said casing part.

In testimony whereof, I have signed my name to this specification.

DIDRICK DYRESEN.
